UNITED STATES PATENT OFFICE.

LUCAS ROMANSON, OF FISHERTON, MANITOBA, CANADA.

DESIGN FOR A SELF-SETTING MOUSETRAP.

59,129.

Specification for Design. Patented Sept. 20, 1921.

Application filed May 4, 1921. Serial No. 466,705. Term of patent 7 years.

To all whom it may concern:

Be it known that I, LUCAS ROMANSON, a citizen of Ukrainia, and a resident of Fisherton, in the Province of Manitoba and Dominion of Canada, have invented a new, original, and ornamental Design for Self-Setting Mousetrap, of which the following is a specification, reference being had to

the accompanying drawing, forming part thereof.

The figure is a front view of a selfsetting mousetrap showing my new design.

I claim—

The ornamental design for a self-setting mousetrap as shown.

LUCAS ROMANSON.
